TORPEDO DIRECTOR

Raymond E. Crooke, Great Neck, N. Y., assignor to
 Ford Instrument Company, Inc., Long Island
 City, N. Y., a corporation of New York

Application May 15, 1941, Serial No. 393,565

4 Claims. (Cl. 235—61.5)

1

This invention relates to a torpedo director and more particularly to a torpedo director for determining the gyro angle setting for a torpedo to be discharged from a torpedo tube which is fixed with respect to the firing ship, so that the torpedo has to describe a curved path until it has attained the direction of the straight path to the point of intercept with the target.

The principal object of this invention is to provide mechanism for computing the gyro angle for the torpedo including an offset or parallax angle to allow for the curved portion of the torpedo's path.

Another object is to provide mechanism to determine and indicate the distance the torpedo will be required to run to reach the point of intercept with the target.

Another object is to provide mechanism, which, when set in accordance with known values representing the present relative positions of the target and firing ship and the rate and direction of movement of the target, will automatically indicate the gyro angle or direction of straight run of the torpedo and the distance the torpedo must run to reach the point of intercept with the target.

Other objects of the invention will be apparent from a consideration of this specification and the accompanying drawings.

The various objects of the invention are attained by mechanism which includes dials representing the relative position and direction of movement of the target and firing ship and hand cranks or automatic means for setting the dials including a sight which may be trained to be pointed at the target. A component solver is angularly set by the means for setting the dials so that the angular position of its vector member represents the direction of movement of the target relative to the present line of bearing between the observing sight and the target and the length is set to represent the speed of the target. The movement of the two component slides of the component solver represent the components of the target speed along and across the present bearing line from the firing ship to the target.

A pair of multipliers are provided wherein the component rates of movement of the target as determined by the component solver are multiplied by the time of run of the torpedo to give output movements representing the component distances the target will move during the time of run, along and perpendicular to the set line of bearing to the target.

The component slides of a vector solver are

2

set in accordance with the component of movement of the target perpendicular to the line of bearing to the target, and in accordance with the present range to the target modified by the range component of distance moved by the target during the time of run. The resulting angular position of the vector member of the vector solver therefore represents the angular offset of the point of intercept from the set line of bearing and the length of the vector represents the distance from the observing point to the point of intercept.

A pair of cam mechanisms, whose input members are positioned in accordance with the distance from the observing point to the point of intercept and the direction of the torpedo path or gyro angle relative to the torpedo tube, determine (1) a correction factor to be included in the determination of the gyro angle to allow for the offset due to the curved portion of the torpedo path, and (2) a correction to be applied to the distance from the observing point to the point of intercept to give a value which when divided by the torpedo speed will give the time of run of the torpedo.

A correction factor is also determined to modify the gyro angle to allow for the effect of the rotation of the earth on the gyroscope of the torpedo during the time of run.

The preferred form of mechanism for carrying out the invention is shown in the accompanying drawings, in which:

Fig. 1 is a geometrical sketch showing the relation of the factors involved in solving the problem;

Figs. 2 and 3 taken together are a diagrammatic representation of mechanism for solving the problem indicated in Fig. 1.

Referring particularly to Fig. 1, the observing point or periscope of the firing ship is represented as o and the course of the firing ship relative to north (N) is represented as Co . The target is represented at b as proceeding on a course CT relative to north. The path of the torpedo is represented as a curve extending from o to the line ac into which it merges when the torpedo settles down on its steady course. The line ac is obtained by extending in a reverse direction the line representing the path of the torpedo after it has settled on its steady course, until it intersects the line representing the extended centerline of the firing ship or more specifically the centerline of the torpedo tube. The point of intercept or the advance position of the target, that is, where the torpedo hits the target is rep-

resented as c . The gyro angle of the torpedo and therefore the direction of the straight portion of the path of the torpedo with reference to the centerline of the firing ship is represented as $G2$. The relative bearing of the target from the periscope of the firing ship and measured from the centerline of the firing ship is represented as BS and the true bearing relative to north is represented as B . It will be seen that the relation of these angles may be expressed as

$$B = Co + BS \quad (1)$$

The target angle or track angle of the target is represented as BT which is the angle from the centerline of the target to the line of bearing to the firing ship as viewed from the target. It will be seen that this angle may be expressed as

$$BT = (180^\circ + B) - CT \quad (2)$$

The present or observed range of the target from the firing ship is represented by R and the distance from the observing point o to the point of intercept c is represented as oc or $R1$. The actual run of the torpedo is represented as $R2$.

The line bc represents the travel of the target during the run of the torpedo and may be expressed as

$$bc = t \cdot ST \quad (3)$$

in which t represents the time of run of the torpedo and ST represents the speed of the target.

The components of the travel of the target, line bc , taken along and perpendicular to the bearing line ob are represented as $t \cdot YT$ and $t \cdot XT$ respectively and may be expressed mathematically as

$$t \cdot YT = -t \cdot ST \cdot \cos BT \quad (4)$$

$$t \cdot XT = t \cdot ST \cdot \sin BT \quad (5)$$

The angle DT is the angular displacement of the point of intercept c relative to the line of bearing ob as measured from the observing point o . This angle DT is the angular offset which would be required from the line of bearing ob for a fictitious torpedo discharged from the point o . The angle $G1$ represents the course of such a torpedo measured from the centerline of the firing ship. It will be seen that the value of this angle may be expressed mathematically by the equation

$$G1 = BS + DT \quad (6)$$

The angle PG is a form of parallax angle required to convert the angle $G1$ to the angle $G2$ to allow for the curvature of the path of a real torpedo discharged from a bow tube of the firing ship. This angle PG may be determined as a function of the run of the torpedo $R2$ and the gyro angle $G2$ or of the distance $R1$ and the angle $G1$. The value of the gyro angle $G2$ may be expressed as

$$G2 = BS + DT + PG \quad (7)$$

Referring to Figs. 2 and 3, the observed relative bearing (BS) of the target is obtained from the sight or periscope 1 which is trained on the target by means of the crank 2 acting through the shaft 3 and worm 4 to turn the worm gear 5 on which the sight is mounted. The shaft 3 also drives a dial 6 by means of gears 7 . The dial 6 represents the firing ship and when read against the fixed index 8 indicates the observed or present relative bearing of the target.

The course of the firing ship is received by the receiver motor 9 which is actuated by a master compass transmitter (not shown). The receiver motor 9 actuates control contacts 10 for the servo or follow-up motor 11 which drives the shaft 12 and a response connection 13 to the receiver mo-

tor 9 in the well known manner so that the rotation of shaft 12 represents the course of the firing ship. The shaft 12 may be positioned by means of the hand crank 14 in case of failure or absence of the receiver motor 9 and servo motor 11 . The hand crank 14 is connected to the shaft 12 by means of the coupling 15 when desired.

The shafts 3 and 12 , the rotation of which represent relative bearing (BS) and firing ship's course (Co), respectively, are connected to shaft 16 through differential 17 . The rotation of shaft 16 represents the true bearing (B) of the target as will be seen from Equation 1. The shaft 16 drives a ring dial 18 surrounding the firing ship dial 6 through gears 19 and a second ring dial 20 through gears 21 . The ring dial 20 surrounds a target dial 22 . The ring dial 18 indicates true bearing (B) of the target when read against the fixed index 8 and course of the firing ship (Co) when read against the bow of the firing ship image on the dial 6 .

The ring dial 20 when read against the fixed index 23 indicates the complement of the true bearing (B) as indicated by the ring dial 18 read against the fixed index 8 . The target dial 22 indicates target course (CT) when the bow of the target image is read against the ring dial 20 and target angle (BT) or track angle is obtained or set by reading the target dial 22 against the fixed index 23 . The target dial 22 is set relative to the ring dial 20 by means of a hand crank 24 and shaft 25 which actuate shaft 26 through differential 27 . The third member of differential 27 is connected to shaft 16 , the rotation of which represents true bearing (B). The rotation of the hand crank 24 and shaft 25 represent target course (CT). It will be seen from Equation 2 that the rotation or position of shaft 26 and dial 22 represent target angle (BT).

Shaft 26 , the rotation of which represents target angle, also controls the angular position of the vector of a component solver 28 through gears 29 and vector gear 30 . The length of the vector or radius to the pin 31 which is slidably mounted in a radial slot in the gear 30 is controlled by a spiraled cam in the gear 32 concentrically mounted to gear 30 . The gear 32 is rotated relative to the gear 30 by a hand crank 33 and dial 34 the rotation of which represent target speed (ST).

The dial 34 is rotated by a worm 35 mounted on shaft 36 to which is secured the hand crank 33 .

The shafts 26 and 36 are connected to gear 32 through a differential 37 , shaft 38 and gears 39 .

The component slides 40 and 41 of the component solver 28 are located by the pin 31 to represent the component YT of the rate of movement of the target along the line of bearing ob and the component XT of the rate of movement of the target across or perpendicular to the line of bearing. It will be seen that the position of the slide 40 may be expressed by the equation

$$YT = -ST \cos BT \quad (8)$$

and the position of the slide 41 may be expressed as

$$XT = ST \sin BT \quad (9)$$

The slide 40 has a rack 42 which meshes with a gear 43 to position a shaft 44 in accordance with the component YT and the slide 41 has a rack 45 which meshes with a gear 46 to position a shaft 47 in accordance with the cross component (XT) of the rate of movement or speed of the target (ST).

The shaft 44 , the rotation of which represents the component YT , positions one input of a con-

ventional multiplier mechanism 48 and the shaft 47, the rotation of which represents the component XT , positions one input of a second conventional multiplier 49. The second input of both multipliers is positioned by shafting 50 the rotation of which represents the time of run (t) of the torpedo. The means for determining the time of run (t) and for rotating the shaft 50 in accordance therewith will be described later. The rack 51 on the output slide of the multiplier 48 positions a shaft 52 through gears 53 in accordance with the product $(t \cdot YT)$ of the inputs. See Equation 4. The rack 54 on the output slide of the multiplier 49 positions a shaft 55 through gear 56 in accordance with the product $t \cdot XT$ of the inputs. See Equation 5.

The present or observed range (R) is set into the mechanism by hand crank 57 and dial or counter 58 which are connected by shaft 59. The shafts 52 and 59 are connected to shaft 60 through differential 61 so that the rotation of shaft 60 represents the present range modified by the component along the line of bearing of the movement of the target during the time of run of the torpedo. The value represented by the shaft 60 may be expressed as $R + t \cdot YT$.

The values of the angle DT and the distance $R1$ are obtained from a vector solver 62, the component slides 63 and 64 of which are positioned in accordance with the modified range represented by the rotation of shaft 60 and the cross component of movement of the target during the run of the torpedo represented by the rotation of shaft 55. The resulting vector angle represents the angle DT and the length of the vector represents the distance oc or the run $R1$ of the fictitious torpedo. The vector consists of a gear 65 having a radial slot in which a pin 66 is positioned at the intersection of slots in the component slides 63 and 64. While this unit is in effect a vector solver, for mechanical purposes it is actually shown in Fig. 3 as a component solver, that is, the pin 66 is located radially of the gear 65 by a servo-motor 67 and the gear 65 is rotated by a servo-motor 68. The pin 66 is moved by the motors 67 and 68 until the positions of the component slides 63 and 64 correspond to the values represented by the rotation of shafts 60 and 55 respectively.

The motors 67 and 68 are controlled by the control contacts 69 and 70 respectively. The control contacts 69 are actuated by a differential 71 interconnecting the shaft 60 and a shaft 72 which is rotated in accordance with the position of component slide 63 by gears 73 and a rack 74 on the slide 63. The control contacts 70 are actuated by a differential 75 interconnecting the shaft 55 and a shaft 76 which is rotated in accordance with the position of component slide 64 by gears 77 and a rack 78 on the slide 64.

The motor 67 positions the pin 66 radially of the gear 65 by a screw 79 threaded through a slide block 80 on which the pin 66 is mounted. The screw 79 is driven by gears 81, shaft 82, differential 83, and shaft 84 which is connected to the motor 67. The motor 68 rotates the gear 65 through shafting 85 and gears 86. The shafting 85 also connects to one member of differential 83 which thereby acts as a compensating differential so that the rotation of the vector gear 65 does not alter the relative rotation of the screw 79 and the shaft 84. The counter 87 driven by shaft 84 therefore represents the length of the vector or the distance $R1$. The shafting 85, the rotation of which represents the angle DT , is

connected to a differential 88 (see Fig. 2) where it is combined with the position of shaft 3 which represents the relative bearing (BS). The output of differential 88 is connected to shafting 89, the rotation of which represents the angle $G1$ as will be seen from Equation 6.

The time of run $t1$, for the fictitious torpedo to travel from the point o to the point of intercept c , is expressed by the equation

$$10 \quad t1 = \frac{R1}{SG} \quad (10)$$

in which SG represents the normal speed of the torpedo. It is obvious that the time of run (t) of the actual torpedo in traveling its longer path will be longer than the time $t1$ and that the amount of this increased time is a function of the angle $G1$ and the distance $R1$. The time of run (t) may therefore be expressed by the equation

$$20 \quad t = \frac{R1 + RC}{SG} \quad (11)$$

in which RC represents a correction which is a function of the angle $G1$ and distance $R1$.

25 The correction RC is computed by a cam mechanism 90 the inputs of which are the shaft 84 and shafting 89, the rotation of which represents the distance $R1$ and the angle $G1$ respectively. The cam mechanism may be of any suitable form and for the purpose of illustration is shown as consisting of a three dimensional or barrel cam 91 which is rotated in accordance with the rotation of shafting 89 which represents the angle $G1$. The cam follower 92 is mounted on an arm 93 which is rotatably mounted on a threaded shaft 94 which is driven by shaft 84 so that the arm 93 and the cam follower 92 are moved along the cam 91 in accordance with the distance $R1$. The cam follower 92 is held against the cam 91 by the spring 95 and the resultant movement of the arm 93 is transmitted to the elongated pinion 96 by the sector 97 which is integral with the arm 93. The rotation of the elongated pinion 96 represents the correction RC .

40 The shaft 98 is driven by the elongated pinion 96 so that its rotation also represents the correction RC . The shaft 99 is driven by differential 100 in accordance with the rotations of shafts 84 and 98 which represent the distance $R1$ and the correction RC respectively.

45 The shaft 50, previously referred to, is driven in accordance with the time of run (t), as expressed in Equation 11, by the output of a dividing mechanism 101, the inputs of which are driven by shaft 99 and a shaft 102 in accordance with the value of $R1 + RC$ and the torpedo speed (SG) respectively. The shaft 102 is positioned by a hand crank 103 and a dial 104 which is driven by a worm 105.

50 The parallax angle (PG) is obtained from a cam mechanism 106 the inputs to which are the shafts 84 and 89 the rotations of which represent the distance $R1$ and the angle $G1$ respectively. The cam mechanism 106 is in all respects

65 the same as cam mechanism 90 except that the cam is so shaped that the output drives shaft 107 in accordance with the angle PG . The rotation of shaft 107 combines in differential 108 with the rotation of shaft 89, which represents the angle $G1$, to rotate the shaft 109 in accordance with the gyro angle ($G2$) as may be seen from Equation 7.

70 It will be seen from Fig. 1 that the direction of the straight portion of travel of the real torpedo relative to the bearing line ob is equal to the sum

of the angles DT and PG. Shaft 110 (see Fig. 2) is rotated in accordance with this sum by the differential 111 which is connected to shafting 85 and shaft 107, the rotations of which represent the angles DT and PG respectively. Shaft 110 is connected to ring dial 112 surrounding target dial 22 and ring dial 20. The arrow 113 on the dial 112 when read relative to the bow of the target image on dial 22 indicates the angle of impact (AG) of the torpedo. The position of the arrow 113 relative to the fixed index 23 represents the direction of the torpedo course relative to the bearing line ob which angle is equal to the sum of the angles DT and PG.

When the time of run is relatively long it is known that, except at the equator, the rotation of the earth has an appreciable effect on the direction of the spin axis of an azimuth gyroscope such as used to guide a torpedo. This effect is expressed by the equation

$$PL = \frac{t \cdot \sin L}{4} \quad (12)$$

in which PL represents the correction in minutes of arc to be applied to the gyroscope, t is the time of run in seconds and L is the latitude at which the run occurs.

This correction for latitude as it is commonly called is computed by the multiplier 114 the inputs of which are time of run (t) as represented by the rotation of shaft 50 and the sine of the latitude as represented by the rotation of a shaft 115 which is set by a hand crank 116 and a dial 117 which is driven by worm 118 on shaft 115. The dial 117 is graduated in terms of latitude so spaced that the rotation of shaft 115 represents the sine of the latitude set on the dial.

The output of the multiplier 114 rotates shaft 119 in accordance with the latitude correction as expressed in Equation 12. The latitude correction, represented by the rotation of shaft 119, is combined with the uncorrected gyro angle (G2) represented by the rotation of shaft 109, in differential 120 to rotate shaft 121 in accordance with the corrected gyro angle. The shaft 121 drives a dial 122 by means of a worm 123. The dial 122 is graduated in terms of gyro angle. A transmitter 124 is driven by shaft 121 to transmit the gyro angle to a receiver unit (not shown) at the torpedo discharge station for use in setting the gyroscope angle of the torpedo.

It will be understood of course that while one specific embodiment of the invention has been described, various changes and modifications may be made therein without departing from the spirit and scope of the invention.

Having described my invention, what I claim and desire to secure by Letters Patent is:

1. Apparatus for use in determining the course to be given to torpedoes, comprising means for determining the direction of the line of sight to a moving target, a component solver including a vector element adjustable in accordance with the target speed and the target course relative to the line of sight, a component member representing the component of target course and speed at right angles to the line of sight and a second component member representing the component of target course and speed along the line of sight, multiplying means including an input element operable in accordance with the movement of the first mentioned component member, a second input element settable in accordance with the time of run of the torpedo, and an output member representing the product of the val-

ues represented by the position of the input elements, second multiplying means including an input element operable in accordance with the movement of the second component member, a second input element settable in accordance with the time of run of the torpedo, and an output member representing the product of the values represented by the position of the input elements, means settable in accordance with the present range to the target, and a vector solver including a component member settable in accordance with the output of the first mentioned multiplying means, a second component member settable in accordance with the combined movement of the output of the second multiplier and the range settable means and a vector member operably associated with said component members and adjusted thereby to determine the distance to the point of intercept of the torpedo and target and the direction of the course of the torpedo relative to the line of sight.

2. Apparatus for use in determining the course to be given to torpedoes, comprising means for determining the direction of the line of sight to a moving target, a component solver including a vector element adjustable in accordance with the target speed and the target course relative to the line of sight, a component member representing the component of target course and speed at right angles to the line of sight and a second component member representing the component of target course and speed along the line of sight, multiplying means including an input element operable in accordance with the movement of the second component member, a second input element settable in accordance with the time of run of the torpedo, and an output member representing the product of the values represented by the position of the input elements, second multiplying means including an input element operable in accordance with the movement of the second component member, a second input element settable in accordance with the time of run of the torpedo, and an output member representing the product of the values represented by the position of the input elements, means settable in accordance with the present range to the target, a vector solver including a component member settable in accordance with the output of the first mentioned multiplying means, a second component member settable in accordance with the combined movement of the output of the second multiplier and the range settable means and a vector member operably associated with said component members and adjusted thereby to determine the distance to the point of intercept of the torpedo and target and the direction of the course of the torpedo relative to the line of sight, means settable in accordance with the torpedo speed, and dividing means including an input element operable in accordance with the distance to the point of intercept as determined by the vector member, a second input element operable in accordance with the torpedo speed settable means and an output member representing the quotient of the values represented by the position of the input elements, said quotient representing the time of run of the torpedo.

3. Apparatus for use in determining the gyro angle relative to the centerline of a torpedo tube for discharging torpedoes having a course consisting of a curved section and a straight section, directing means for determining the direction of the line of sight to a moving target relative to the centerline of the tube, means for determining the

component at right angles to the line of sight of the movement of the target during the time of run of the torpedo, means for determining the component along the line of sight of the movement of the target during the time of run of the torpedo, said component determining means including means adjustable in accordance with the time of run of the torpedo, means settable in accordance with the range to the target along the line of sight, a vector solver including component members operable in accordance with the component determining means and the range settable means and a vector member operably associated with said component members the direction and length of which represent the direction relative to the line of sight and the distance to the point of intercept of the torpedo and target, differential means for combining the directional position of the directing means and the directional position of the vector member to determine the direction of the point of intercept relative to the centerline of the tube, means settable by the differential means and in accordance with the length of the vector member for positioning an output member representative of a correction to the distance to the point of intercept, means for combining the positions of the output member and the length of the vector member, dividing means including an input element operable by the combining means, a second input element operable by a member settable in accordance with the torpedo speed and an output element positioned thereby in accordance with the time of run of the torpedo, means for adjusting the said time of run means in accordance with the position of the output element, means settable by the differential means and in accordance with the length of the vector member for displacing a part in accordance with the correctional angle to allow for the curved section of the torpedo path and second differential means for combining the output of the first differential means and the displacement of the part to determine the direction of the straight section of the torpedo path relative to the centerline of the torpedo tube.

4. Apparatus for use in determining the gyro angle relative to the centerline of a torpedo tube for discharging torpedoes having a course consisting of a curved section and a straight section, directing means for determining the direction of the line of sight to a moving target relative to the centerline of the tube, means for determining the component at right angles to the line of sight

of the movement of the target during the time of run of the torpedo, means for determining the component along the line of sight of the movement of the target during the time of run of the torpedo, said component determining means including means adjustable in accordance with the time of run of the torpedo, means settable in accordance with the range to the target along the line of sight, a vector solver including component members operable in accordance with the component determining means and the range settable means and a vector member operably associated with said component members the direction and length of which represent the direction relative to the line of sight and the distance to the point of intercept of the torpedo and target, differential means for combining the directional position of the directing means and the directional position of the vector member to determine the direction of the point of intercept relative to the centerline of the tube, means settable by the differential means and in accordance with the length of the vector member for positioning an output member representative of a correction to the distance to the point of intercept, means for combining the positions of the output member and the length of the vector member, dividing means including an input element operable by the combining means, a second input element operable by a member settable in accordance with the torpedo speed and an output element positioned thereby in accordance with the time of run of the torpedo, means for adjusting the said time of run means in accordance with the position of the output element, means settable by the differential means and in accordance with the length of the vector member for displacing a part in accordance with the correctional angle to allow for the curved section of the torpedo path, second differential means for combining the output of the first differential means and the displacement of the part to determine the direction of the straight section of the torpedo path relative to the centerline of the torpedo tube, multiplying means settable in accordance with the time of run of the torpedo and the sine of the latitude for positioning an output member in accordance with a correctional factor to correct for the effect of rotation of the earth upon the path of the torpedo and means for modifying the determined direction of the straight section of the torpedo path in accordance with the position of said output member.

RAYMOND E. CROOKE.
